UNITED STATES PATENT OFFICE.

EDWARD F. SCHORNDORFER, OF CLEVELAND, OHIO, ASSIGNOR OF ONE-FOURTH TO
W. E. DEFENBACHER, OF CANAL DOVER, OHIO, ONE-FOURTH TO G. E. BARTHOLO-
MEW, OF EUCLID, OHIO, AND ONE-FOURTH TO J. F. DEFENBACHER, OF CANAL
DOVER, OHIO.

WINDOW-GLASS-CLEANING DEVICE.

1,027,359.

Specification of Letters Patent. Patented May 21, 1912.

Application filed March 14, 1911. Serial No. 614,361.

To all whom it may concern:

Be it known that I, EDWARD F. SCHORNDORFER, citizen of the United States, residing at Cleveland, in the county of Cuyahoga and State of Ohio, have invented certain new and useful Improvements in Window-Glass-Cleaning Devices, of which the following is a specification.

My invention relates to improvements in window-cleaning devices, and more particularly to such devices as are employed for cleaning the windows of a moving vehicle, such as an electric trolley car or automobile, from adhering snow or rain.

My invention will be briefly explained as applied to the wind-shield of an automobile; making reference to its use, as well, upon the window of a trolley car.

My said improvements relate especially to the means for adjusting the device to different thicknesses of glass and different window frames; to the means for securing an even pressure of the wiper upon the surface of the glass; to the means for effecting both radial and lateral movement of said wiper; to the means for permitting the lateral travel of the device upon the supporting rail without injuring or marring the same; and to other details which will be more fully set forth in connection with the accompanying drawings, wherein:

Figure 1 is a view in elevation of the rear or inner face of a model wind-shield to which my improvement is applied for illustrative purposes; Fig. 2 is a vertical sectional view thereof; Fig. 3 is an enlarged median sectional view of the device, partly broken away; Fig. 4 is another fragmentary view of the device partly assembled, particularly showing the spring and mounting rollers; Fig. 5 is a top view; Fig. 6 an end view; Fig. 7 a side view of the wiper or cleaning-member; Fig. 8 is a rear view of a window-frame to which my pivoted cleaning device is applied; Fig. 9 is a fragmentary view, partially in vertical section and upon an enlarged scale, better illustrating the slide and spring; Fig. 10 is a front view, partially in section, showing the slot for accommodating the bearing-sleeve, and Fig. 11 is another fragmentary view, showing the slide and spring.

Throughout the several figures of the

drawings I have employed the same characters of reference to indicate similar parts. 55

Referring first to Figs. 3 and 9, wherein there are shown in enlarged detail the several parts of my improvement, it will be noticed that the wiper or cleaner *a* is mounted upon a round, rectangularly-bent rod *b* 60 which passes through the sleeve *c*, forming a pivotal mounting for the wiper. Said sleeve *c* is provided with a thumb-nut *c'* which makes the same adjustable to accommodate various top or side rails whereon the 65 device may be mounted. The protruding end of rod *b* has an adjustable arm *d* securely mounted thereon by means of the set-screw *d'*, this arm carrying an adjustable bearing-roller *d*² and support *d''*. 70

The above described parts form the elements of the window-cleaning device, which may either be mounted within the side-rail as indicated at *x*, Fig. 1, and shown in Fig. 8, or these members, instead, may be applied 75 to the roller mounting which also forms a part of my invention. The latter comprises a U-shaped spring *e* within frames or slides, vertically slotted at *e''*, which receive the sleeve *c*, which has a vertical adjustment 80 within the duplicated slides *f*, *f*, for accommodating different sizes or shapes of top-rails, as respectively indicated in Figs. 1, 2, 3 and 4. These slides *f*, *f*, respectively carry the lateral rollers *f'*, *f''*, and the extended 85 feet *f'''*. There is also provided an upper roller *c''* surrounding sleeve *c*, and a hinged bifurcated member *e''* which is adapted to embrace the rod *d*, as indicated in Figs. 2 and 3, to prevent its rotary movement; or it 90 may be swung into the plane of the extended limb of spring *e* in order to free the said arm, as desired. In addition to these details, I may also explain the following preferred features of construction, to which, 95 however, my invention is not necessarily restricted:—The wiper *a* consists of two stampings *a''* centrally slotted at *a²* and provided with a recess *a³*. Between these stampings there is secured a rubber strip *a⁴*, 100 which may readily be renewed by removing screws *a⁵*. Within the recess *a³* there is provided a collar *b'*, held in place on rod *b* by its set-screw *b''*. A pin or stud *b²* screwed into rod *b* normally lies within the slot *a²* 105 of the wiper *a*, which, of course, may be of

any suitable length, as indicated by the broken away portions in Figs. 3, 5 and 7. With this device mounted upon the top-rail g of a wind-shield, as in Figs. 1 and 2, it will now be understood how it may be used, either for cleaning an arc-shaped portion of the window, or for moving the cleaner from side to side; thus with rod d held from turning by means of the bifurcated member e'' , the entire device may be moved bodily from one side of the wind-shield to the other, sweeping a path the width of wiper a entirely across the same. The position of the wiper may be adjusted upon the wind-shield merely by releasing the set-screw b'' and sliding the collar downward or upward along the rod b , whereon it may again be secured in adjusted position. In order to sweep the wiper or cleaning-member through an arc, it is necessary merely to swing the member e'' to the position shown in Fig. 4, when said wiper may be moved by means of rod d through an arc, as indicated by the dotted lines in Fig. 1. In order to secure an even pressure of the wiper a against the glass, the bearing roller d'' may be adjusted lengthwise of rod d so that said roller engages the glass at the point desired, and its pressure may be varied by altering the angular position of said bearing roller on rod d , through the said set-screw d^s . The wiper a in addition may be turned out of engagement with the glass, if desired, merely by releasing the screw b'' , sliding the wiper the length of slot a' and turning it so that the stop or stud b^2 will lie within the angular end portion of said slot a' . As shown in Figs. 3 and 4, the rollers are provided both with concave and flattened surfaces, so that either a flattened or rounded top-rail of a wind-shield may be suitably accommodated, while the spring e permits considerable variation in the thickness of these parts. However, as features of my invention are not limited to wind-shields, I may refer to the use of the same in connection with the side or top rail of an ordinary window, such as is required for the motorman of a trolley car. Thus at z , Fig. 1, the devices provided for lateral travel of the wiper are shown as having been dispensed with and the sleeve or other suitable bearing is provided in the side-rail for rod b , while rod d (shown broken away), is attached to its protruding end. In this position, of course, the wiper is afforded merely an arc-shaped path, but for ordinary use this is entirely sufficient. The feature of adjustment provided by adjustably mounting the actuating-rod d upon the angular extension of rod b , affords a considerable accommodation for various thicknesses of frame and glass, while the pressure exerted by the wiper may readily be altered, as desired, by adjusting the bearing roller in its angular

position upon the rod d , as already explained.

Having now described the preferred features of construction, I claim as new and desire to secure by Letters Patent the following:

1. In a window-cleaning device, the combination with a wiper or cleaning-member, of a rod forming a pivotal mounting therefor, an actuating-member adapted to be adjustably secured upon the extended end of said rod, and a bearing-roller provided upon the actuating-member for engaging the window glass opposite the wiper, substantially as set forth.

2. In a window-cleaning device, the combination with a wiper of an angularly-bent rod forming a pivotal mounting for said wiper, an actuating-member adjustably secured upon the extended angularly-bent end of the rod, means for holding it in adjusted position thereon, an adjustable roller mounting upon the actuating-member, and a roller or wheel for bearing upon the window glass opposite the wiper, substantially as set forth.

3. In a window-cleaning device, the combination with a wiper adapted to bear upon one side of the window of an actuating-member pivotally connected with said wiper and extending adjacent to the opposite surface of the glass, means for temporarily withholding the parts from pivotal movement, and adjustable roller bearings for mounting the device upon a rail of the window, substantially as set forth.

4. In apparatus of the class described, the combination with a U-shaped spring of a pivoted cleaning device connected therewith, comprising a wiper adapted to bear upon one side of the glass, and an actuating-member positioned adjacent to the other side thereof, a frame therefor and roller bearings adapted to travel upon a supporting rail, substantially as set forth.

5. In a window-cleaning device, the combination with separable metal parts affording a tubular slotted sleeve provided with depending edges, of a rubber strip engaged between said edges, a rod mounting the same for pivotal movement, a stud lying within the slot, an adjustable collar retaining the device in position upon the rod, and an actuating-member for imparting pivotal movement to said device, substantially as set forth.

6. In a window-cleaning device of the class described, the combination with an L-shaped rod of a pivotal mounting therefor, a wiper positioned upon the free end of said rod, an actuating-member adjustably secured to the pivoted end of the rod, a bearing-roller thereon; said wiper and bearing roller being designed to press opposite each other upon opposite sides of a window glass; and means for adjustably securing the rod and actuat-

ing-member for common pivotal movement, whereby different thicknesses of glass and frame may be accommodated, substantially as set forth.

- 5 7. In a window-cleaning device of the class described, the combination with an L-shaped rod of a pivotal mounting therefor, a wiper positioned upon the free end of said rod, an actuating-member adjustably secured to the pivoted end of the rod, a bearing-roller thereon; said wiper and bearing roller being designed to press opposite each

other upon opposite sides of a window glass; means for temporarily withholding the pivotal parts against rotation, and a roller bearing for permitting the lateral movement of the device along the mounting-rail of a wind-shield, substantially as set forth. 15

In testimony whereof I do now affix my signature in the presence of two witnesses. 20
